BRINE STORAGE CABINETS

Walter J. Craig, Prospect Heights, Ill., assignor to
K and M Rubber Company, Elk Grove Village,
Ill., a corporation of Illinois

Filed Jan. 28, 1969, Ser. No. 15,542

Term of patent 14 years

Int. Cl. D23—01

U.S. Cl. D23—2

FIG. 1

FIG. 3

FIG. 2

FIG. 5

FIG. 6

FIG. 7

FIG. 8

FIG. 9

FIG. 10

FIG. 1 is a front perspective view of the brine storage cabinet embodying my new design;

FIG. 2 is a side elevational view of the brine storage cabinet of FIG. 1 on a reduced scale;

FIG. 3 is a top plan view thereof;

FIG. 4 is a top plan view of a removable lid element of the cabinet, the cabinet per se being omitted for purposes of disclosure;

FIG. 5 is a front elevational view thereof;

FIG. 6 is a side elevational view of a second embodiment of the brine storage cabinet;

FIG. 7 is a side elevational view of the first embodiment of the brine storage cabinet with a brine control valve being shown in broken lines for illustrative purposes only;

FIG. 8 is a side elevational view of a third embodiment of the brine storage cabinet;

FIG. 9 is a side elevational view of a fourth embodiment of the brine storage cabinet; and

FIG. 10 is a top plan view of FIG. 9.

The brine storage cabinet is fragmentarily shown in FIGS. 2, 6, 7, 8 and 9 for purposes of disclosure.

I claim:

The ornamental design for brine storage cabinets, as shown and described.
